UNITED STATES PATENT OFFICE.

GUSTAV P. HEINRICH, OF BROOKLYN, NEW YORK, ASSIGNOR TO INTERSTATE ELECTRIC NOVELTY COMPANY, OF NEW YORK, N. Y., A CORPORATION OF NEW YORK.

TUBULAR ELECTRIC POCKET-LAMP.

1,141,634.

Specification of Letters Patent. Patented June 1, 1915.

Application filed January 28, 1915. Serial No. 4,820.

To all whom it may concern:

Be it known that I, GUSTAV P. HEINRICH, a subject of the Emperor of Germany, residing at the borough of Brooklyn, Kings county, 5 State of New York, have invented certain new and useful Improvements in Tubular Electric Pocket-Lamps, of which the following is a full, clear, and exact description.

This invention relates to an improvement 10 in tubular pocket-lamps, the object being generally to improve the construction of such lamps.

My improvement relates mainly to pocket-lamps of the electric variety, and has for a 15 particular object to improve the circuit closing mechanism for the lamp and elements coöperating therewith to close the circuit between the battery and circuit closer.

20 I will now proceed to describe my invention in detail, the novel features of which I will point out in the appended claims, reference being had to the accompanying drawing, forming part thereof, wherein—

25 Figure 1 is an elevation of a lamp embodying my improvement; Fig. 2 is a vertical sectional view of a portion of the lamp; Fig. 3 is a detail view, in elevation, showing one of the lamp casing members; Fig. 4 30 is an enlarged sectional plan view, the section being taken on a line 4—4 in Fig. 2; and Fig. 5 is an enlarged vertical sectional detail view, the section being taken on a line 5—5 in Fig. 1.

35 As herein embodied, my improved lamp consists of a plurality of separably connected tubular casing members 1 and 2, detachably connected at the point 3 by bayonet-joint connections 4, or otherwise. The 40 casing, consisting of the members 1 and 2, contains a battery 6, of the dry type, which battery supplies current for the lamp 7, the lamp 7 being connected to the battery 6 in a manner common to this form of electric 45 lamp. In other words, the inner end of the lamp rests in contact with the carbon of the battery, a spring 8 serving to maintain such contact. The spring 8 also aids in conveying the current from the zinc of the battery 50 6 to the circuit closer and casing members 1 and 2, the lamp 7 being in circuit with the casing member 2.

To convey the current from the spring 8 to the casing members, I provide a tubular 55 conductor 9 having in contact therewith one

end of the spring 8, the tubular conductor 9 being insulated from the wall of the casing member 1 by means of a surrounding sleeve 10 of insulating material, such as fiber, the said conductor 10 and spring 8 being insulated from the end of the member 1 by a 60 pad 11.

The circuit closer consists of a tongue 12 integral with the wall of the casing 1. The tongue 12 is formed by punching out the 65 wall of the member 1 as at 13 whereby the resilient tongue 12 is formed. The tongue 12 carries a push-button 14 having a head 15 which will contact with the tubular conductor 9 when said tongue is pressed inwardly. The insulating sleeve 10 is provided with an opening 16 subjacent the tongue 12 which allows the movement of the tongue 12 to take place so that the head 15 may contact with the conductor 9. The 70 interposition of the tubular insulating sleeve 10 between the inner wall of the casing member 1 and the tubular conductor 9 also serves to keep the tongue 12 and head 15 thereon normally out of contact with the 75 conductor 9.

A further feature of my improvement consists of a clip 17 having a tongue 18' for holding the lamp in a pocket. The clip 17 is secured to the casing member 1 as at 18 85 and 19. The body or band portion of the clip 17 is provided with an opening 20 through which the push button 14 protrudes. The body of the clip 17 is positioned over the tongue 12 and acts to protect the same 80 and also cover the slot-like opening 13 to prevent the entrance of foreign matter which might short-circuit the battery 6.

Having now described my invention what I claim and desire to secure by Letters Patent, is:

1. An electric pocket-lamp, comprising a casing consisting of a plurality of detachably connected members, one of said members being cut away to form a yieldable 100 tongue, a tubular conducting element within the casing member carrying the tongue, insulating material located between said conducting element and the casing member which carries the same, a circuit closer carried by said tongue and normally out of contact with the conducting material, said insulating material being cut away in line with said circuit closer whereby said contact can be caused to impinge upon said 105 110

conducting material, a lamp carried by said casing, and a battery within the casing in circuit with said lamp and the conducting element within said casing.

- 5 2. An electric pocket-lamp comprising a casing consisting of a plurality of detachably connected members, one of said members being cut away to form a yieldable tongue, a tubular conducting element with-
10 in the casing member carrying the tongue, insulating material located between said conducting element and the casing member which carries the same, a circuit closer carried by said tongue and normally out of
15 contact with the conducting material, said insulating material being cut away in line with said circuit closer whereby said contact can be caused to impinge upon said conducting material, a lamp carried by said casing,
20 a battery within the casing in circuit with said lamp and the conducting element within said casing, and a fastening device secured to one of said casing members consisting of a clip and a resilient tongue carried thereby, said clip covering the cut out portion in the casing member to which it is secured, said clip being also provided with an opening for the passage therethrough of the circuit closer carried by said tongue.
25 3. An electric pocket-lamp consisting of a casing arranged to contain a battery, said casing being cut away to form a resilient tongue, a circuit closer carried by said tongue, arranged to close the circuit between

said battery and said casing when said tongue is forced inwardly, conducting means within said casing in circuit with said battery but normally out of contact with said circuit closer, and a fastening device carried by said casing and located over said tongue and covering the cut out portion adjacent the tongue, said fastening device having an opening in the body thereof through which the circuit closer can be manipulated.

4. An electric pocket-lamp, comprising a casing, said casing being cut away to form a yieldable circuit-closing tongue, a lamp carried by said casing at one end thereof, a battery within said casing having its carbon-pole in contact with one of the circuit-members of the lamp, insulating material between the battery and said casing, a metallic conductor located between the battery and the insulating material but out of contact with the battery, and an electrical conductor contacting with said metallic conductor and the zinc end of said battery, said insulating material being provided with an opening alining with the circuit-closing tongue whereby said tongue can be caused to contact with said metallic conductor.

Signed at New York city, N. Y., this 19th day of January, 1915.

GUSTAV P. HEINRICH.
